UNITED STATES PATENT OFFICE.

DAVID LINCOLN FRIES, OF CAMBRIDGE, AND HAROLD F. PHILLIPS, OF SOMERVILLE, MASSACHUSETTS.

METHOD OF MAKING ARMOR-PIERCING BULLETS.

1,318,860.

Specification of Letters Patent.

Patented Oct. 14, 1919.

Application filed August 20, 1918. Serial No. 250,660.

To all whom it may concern:

Be it known that we, DAVID LINCOLN FRIES and HAROLD F. PHILLIPS, both citizens of the United States, residing, respectively, 5 at Cambridge and Somerville, in the county of Middlesex, and State of Massachusetts, have invented new and useful Improvements in Methods of Making Armor-Piercing Bullets, of which the following is a specification.

The present invention relates to methods of making jacketed bullets for small arms adapted to pierce armor, and for other purposes. It is already known that the most 15 efficient type of armor-piercing bullet is one having a hardened steel core or body and a jacket of so-called cupro nickel, the same being an alloy of nickel and other metals, the composition of which is well known and understood, and is not a part of our invention. It has been further determined that such 20 jacket should contain a considerable quantity of metal at the point of the bullet; in other words that the point should be of 25 solid metal having relatively considerable mass. It is obviously of importance also that the exterior of the jacket should be smooth and symmetrical whereby to diminish wind resistance and particularly une- 30 qually distributed resistance such as would tend to deflect the bullet in flight.

Bullets of the general type above briefly set forth being known, but the heretofore known methods of making them having certain defects which cause the finished product to be imperfect, it has been our object to devise a new and improved method of making such bullets which will result in a superior product, free from the defects which 40 have characterized "armor-piercing bullets" made according to other methods. Our invention consists principally in an improved method of forming the soft metal jacket of such a bullet or projectile, by which the de- 45 sired quantity of metal is located at the point of the jacket, and such metal is there located in a compact, solid condition, without internal cavities, and equally without external grooves, ridges, or other irregularities which would be liable to impede or deflect the bullet in its flight.

In the drawings wherein we have illustrated the product of this method in different stages of development, and the tools

preferably employed in carrying out the 55 method,

Figure 1 is a sectional view of a drawn cup which constitutes the blank from which the jacket is made. Figs. 2, 3, 4, and 5 are similar views showing the blank in successive stages of development. Fig. 6 is a sectional view of the finished bullet having the hardened steel core or body in place within the soft metal jacket. Figs. 7, 8, 9, 10, and 11 are sectional views showing the complementary punches and dies, that is, the forming tools by which the successive stages of the method are carried out.

The same reference characters indicate 70 the same parts in all the figures.

Nothing in the foregoing statement or in the following description is to be understood as limiting the method to the specific materials or substances herein named as being the preferred materials for making the core and jacket, respectively, of the bullet. Thus the term "hardened steel" used in description of the core is intended to include any form of steel, or other alloy of iron, which is made hard by reason of the composition of its alloy or its treatment; and generically includes any other metal, if such may be made available for the purpose, having hardness comparable to that required of an armor-piercing projectile, and other metals than 85 this may also be used as the cores of bullets having the type of jacket here described. The jacket produced according to our method may be made of any soft metal, whether the specific alloy known as "cupro 90 nickel", or other metal adapted to be employed as a jacket and to serve the peculiar functions served by the nickel jacket on an armor-piercing projectile. Therefore the term "cupro nickel" here used is merely the 95 descriptive typical designation of any metal suitable for the particular purpose.

In carrying out the method we first take a blank, which is in the form of a deep cup *a*, substantially like that shown in Fig. 1, 100 this cup having an external diameter approximately or substantially that of the completed bullet to be made. As the cup is or may be made by familiar old methods which are neither a part of our invention nor modified thereby, we do not here detail the manner of making the cup, but leave it to be understood that the cup is already avail- 105

able. The first step in our process is to indent the bottom of the cup inwardly, forming an inward offset b . This operation may conveniently be performed by tools such as 5 shown in Fig. 7, consisting of a die 1 having a bore which fits the exterior of the cup, and in the bottom of which is placed an anvil or set 2, and a punch 3, which substantially fits the interior of the cup, has an 10 external shoulder 4, and is passed into the cup and forced toward the anvil 2. The end of said punch is recessed, complementally to the anvil 2, whereby it coacts with the latter in indenting the bottom. A shoulder 4 on the punch, bearing on the edge 15 of the cup forces down the walls thereof, and prevents the bottom being sheared by the punch.

The next steps consist in tapering and 20 consolidating the end of the jacket. These steps are performed by a succession of dies 5, 7, 9, and 11, respectively, and complementary punches 6, 8, 10, and 12, respectively. In the die 5 the indented end of the jacket is 25 reduced and tapered somewhat as shown in Figs. 3 and 8, whereby the sides of the indentation b are crowded against the walls of the cup. In the next step, shown in Figs. 4 and 9, the end is still further reduced in 30 diameter and the walls adjacent thereto further tapered with a convex curvature. In this operation also the interior of the jacket adjacent the offset end wall b is shaped to a desired form by the punch 8. In the next 35 step, carried out by the die 9 and punch 10 shown in Fig. 10, the point is further reduced in diameter, the cavity in the point adjacent to the end wall is further closed, and the interior and exterior surfaces 40 brought still nearer to the finished form. In performing the final operation a die 11 and punch 12 (Fig. 11) are used, which have the final finished form of the exterior and interior, respectively, of the jacket, and there- 45 by the end cavity is wholly closed and the jacket is given the required taper, curvature, and symmetry; while the interior is formed to fit the core.

Finally the steel core c is inserted in the 50 jacket and the open end of the latter is flanged over the base of the core by any suitable means in any desired way as shown in Fig. 6.

This series of operations produces a jacket 55 having the desired form and characteristics and particularly possessing at the nose d a solid mass of metal sufficient in quantity to produce the desired effect of softening or cushioning the impact of the projectile striking an armor plate, thus diminishing the tendency to rebound and the tendency to shatter the hardened core, and lubricating the core in its entrance into and passage through the armor plate. Of particular importance is the fact that this par-

ticular method enables a smooth and symmetrical exterior surface to be given the jacket, and that not only are there no external fins, ridges, or other superficial irregularities formed or left in the finished product, but there is no tendency whatever to form such irregularities, since even at the beginning of the condensing operations the outer surface of the jacket is smooth and continuous. We include within 75 the term "condensing operations", all those operations subsequent to the step of indenting the end of the cup, shown in Figs. 2 and 7, by which the point or nose of the jacket is reduced in diameter and the metal 80 contained in the cup end wall and in the side walls adjacent thereto, is compacted, condensed, and consolidated into a substantially homogeneous mass.

We do not restrict our invention to the 85 precise number of operations hereinbefore described, for I conceive that it may be possible under some circumstances to omit some of these operations, while on the other hand, it may be desirable or necessary to 90 carry out the condensing part of the method in a greater number of steps than is here shown. Essentially the invention consists, first, in the step of indenting the bottom of the cup to form an inner protuberance b , 95 and thereafter condensing such end into the final desired form and mass, whatever may be the number of steps required for carrying to completion this condensing operation. The concluding step, of inserting the hardened steel core in the jacket and bending or spinning the end of the latter over the base of the core is or may be the same in our method as in methods previously used in producing such bullets or projectiles. 100

The foregoing description of the implements or means preferably used in carrying out our method is not intended as in any sense a limitation of the claimed invention to any specific means, but is merely the 110 part of the disclosure of an operative means for carrying the invention into effect, whereby to enable others skilled in the art to practice our invention. As concerns the application of power to the members of the 115 several punch and die couples herein shown, power may be applied in any way and by any means suitable for the purpose.

While we have previously indicated the 120 particular utility of the invention for making small arms ammunition, we have not intended thereby to indicate or imply any limitation of the scope of the invention. The same principles are applicable to the 125 production of bullets or projectiles of all calibers adapted to be provided with soft metal jackets of the sort here indicated, wherefore we claim the novel features in the process herein described, without any 130 limitations as to the size of the articles.

operated on or of the finished products, or as to the use to which finished articles are put; that is, whether they are actually used to pierce armor or to penetrate other substances than armor. The invention is concerned with the method of making the jacket and assembling it with a core, wherefore we claim such method independently of the specific material of the jacket 10 or of the core, or the use to which the bullet is put.

What we claim and desire to secure by Letters Patent is:

1. The method of making jacketed projectile which consists in providing a cup of 15 relatively soft and ductile metal, indenting the end wall of said cup inwardly, closing and compacting the indented end of such cup and tapering such end, and placing a 20 core within the jacket so formed.

2. The method of forming a jacket for a projectile which consists in first providing a substantially cylindrical cup, then indenting the end wall of said cup inwardly, and then forcing the end of the 25 jacket having such end wall symmetrically toward the axis, in such manner as to compact such end into a substantially solid tapered nose.

3. The method of forming a soft metal jacket for a projectile which consists in providing a cup having an end wall, offsetting the center of such end wall inwardly 30

into the cup, and then compacting such end of the cup and the wall thereof by successive steps into a substantially solid nose, at the same time forming an external convex taper in such nose and the adjacent walls of the cup. 35

4. The method of forming a soft metal 40 jacket for a projectile which consists in providing a cup having an end wall, offsetting the center of such end wall inwardly into the cup, and then compacting such end of the cup and the wall thereof 45 by successive steps into a substantially solid nose, at the same time forming an external convex taper in such nose and the adjacent walls of the cup, and also simultaneously giving the interior of the jacket a predetermined form adapted to fit a metal core. 50

5. The method of making a soft metal jacket having a solid nose containing a considerable mass of material, for a projectile which consists in first forming a cup 55 having an end wall, then indenting the central part of said end wall inwardly, then swaging the end of the cup surrounding said end wall inwardly toward the axis from all sides, and at the same time confining the metal of such end wall within the cup. 60

In testimony whereof we have affixed our signatures.

DAVID LINCOLN FRIES.
HAROLD F. PHILLIPS.
